US0D1016924S

(12) **United States Design Patent** (10) **Patent No.:** **US D1,016,924 S**
(45) **Date of Patent:** **** Mar. 5, 2024**

(54) **SCOOTER**

(71) Applicant: **Yadea Technology Group Co., Ltd**,
Wuxi (CN)
(72) Inventors: **Junfeng Dong**, Jiangsu (CN); **Xutao Zou**, Jiangsu (CN); **Hongbin Ye**, Jiangsu (CN); **Dong Zheng**, Jiangsu (CN)

(**) Term: **15 Years**

(21) Appl. No.: **35/515,427**

(22) Filed: **Jul. 25, 2022**

(80) **Hague Agreement Data**

Int. Filing Date: **Jul. 25, 2022**

Int. Reg. No.: **DM/224035**

Int. Reg. Date: **Jul. 25, 2022**

Int. Reg. Pub. Date: **Oct. 21, 2022**

(30) **Foreign Application Priority Data**

Jul. 15, 2022 (CN) 202230449841.6
